UNITED STATES PATENT OFFICE.

ABBOT A. LOW, OF HORSESHOE, NEW YORK, ASSIGNOR TO MAURICE J. WOHL AND HARRY HERTZBERG, BOTH OF NEW YORK, N. Y., AND ABBOT A. LOW, OF HORSESHOE, NEW YORK, TRUSTEES.

ARC-LAMP CONSTRUCTION.

1,033,813.

Specification of Letters Patent. Patented July 30, 1912.

Application filed March 16, 1908. Serial No. 421,568.

To all whom it may concern:

Be it known that I, ABBOT A. Low, a citizen of the United States, and resident of Horseshoe, in the county of St. Lawrence 5 and State of New York, have invented certain new and useful Improvements in Arc-Lamp Construction, of which the following is a specification.

This invention relates to arc lamps employing an expansible thermal conductor for controlling the feed of the movable electrode or carbon. Such a thermal conductor, being preferably in the form of a wire having sufficient resistance to become heated by 10 the passage of current therethrough, the resulting variations in expansion controlling the feed of the carbon, is naturally a somewhat delicate instrumentality for the purpose.

20 The object of the present invention is so to reduce the friction of the moving parts connected with this thermal conductor, that the condition of the mechanism may be termed "floating."

25 To this end, the invention may be said to consist in the novel features hereinafter described, illustrated in the drawings, and more particularly set forth in the claims.

In the drawings, Figure 1 is a side elevation of an arc lamp embodying the improvements; Fig. 2 is a horizontal section through the movable electrode carrier; Fig. 3 is a similar view of a modified form of carrier; Fig. 4 is a horizontal section 30 through the bearing for the lever connected immediately to the thermal conductor; Fig. 5 is a side view of this bearing; and Fig. 6 is a fractional, sectional view of a modified form of carbon carrier.

40 Referring to these drawings, the frame of the lamp, which may be considerably varied, is shown as comprising upright rods 1, top and bottom plates 2 and 3, and an intermediate plate or platform 4. Depending 45 from the bottom plate 3 is the lower, fixed electrode holder 5; 6 being the fixed electrode.

50 7 is the upper, movable electrode holder, here shown as in the form of a split resilient tube. This holder 7 is mounted in a block or carrier 8, the sides of which are grooved at 9 to receive the rods 1.

10 is the movable electrode in holder 7. The feed of electrode 10 is immediately con-

trolled by a clutch 11, which embraces the 55 electrode and rests upon the platform 4. From the end of this clutch member 11 a link 12 extends upward to the outer end of a lever 13, which is fixed to a rock-shaft 14 journaled in a bracket 14' secured to one of 60 the rods 1. Connected to the lever 13 at opposite sides of its pivot is a thermal conductor or wire 15, the outer ends of this conductor being connected to spring supports 16. A compensating wire 17 also connects 65 these spring supports, but, unlike conductor 15, is intended to carry no current. Conductor 15 and wire 17 are of such nature that they expand and contract equally under the influence of variations in atmospheric 70 temperature; therefore, such variations cause the wire 17 to vary the flexure of spring supports 16 correspondingly, thus preventing the expansion and contraction of conductor 15, under variations in atmospheric 75 temperature, from affecting the lever 13. The current for the lamp enters conductor 15 through variable resistance 18, passes from the lower end of conductor 15 to the holder 7 by wire 19, from the holder 80 7 to and through the movable electrode 10, the lower electrode 6, the fixed electrode holder 5, and out at 20. It will be understood that contraction of conductor 15, due to a decrease in the amount of current passing 85 therethrough, causes the conductor to turn the lever 13 in one direction; this movement lowering the link 12 and clutch 11, thus permitting the electrode 10 to slide downward under the influence of gravity. The 90 opposite movement of lever 13, and the lifting of clutch 11, to raise the movable electrode, is effected, when conductor 15 expands, owing to increase of current, by a weight 21, mounted on intermediately pivoted lever 22; this lever being connected 95 with lever 13 by a link 23.

All of the features thus far described form the subject matter of the co-pending application of Maurice J. Wohl and Harry 100 Hertzberg, filed Dec. 4th, 1907, Serial No. 405,068, and are not claimed *per se* in the present case.

The features of novelty in the present application will now be described.

105 Fig. 2 shows the block or carrier 8 as of insulating material; Fig. 3 as of metal or other conducting material. It is desired to

provide an insulating ball bearing between this block and the rods 1, to eliminate practically the friction between the block and rods. In Fig. 2, each groove 9 is shown as being provided with horizontally aligned pairs of substantially semi-spherical recesses 25, there being preferably a pair toward the top of the groove and another pair toward the bottom thereof. In these recesses 10 are seated steel or other balls 27, which bear against the rods 1. In Fig. 3 glass balls 28 are similarly disposed, being held in position by a trough-shaped retainer plate 29, which fits in each groove 9, being itself held 15 in place by a screw or screws 30. These plates are provided with apertures registering with the recesses 25; and it will be observed that the complete recesses formed in the block 8 and in the plates are somewhat 20 more than semi-spherical, so that, when the plates are secured in position, the balls are prevented from falling out, even when the block is removed from the rods 1. It is also desired to reduce the friction at the pivot of 25 lever 13. This may be effected in the following manner: In each of the journal apertures of the two cheeks of the bracket 14', between which stands the lever 13, is secured a ball race-way 31, preferably of insulating 30 material. This race-way may be desirably formed of two annular sections 32, each having half of the race-way groove, and being further provided with a flange 33, the two flanges overlying the opposite sides of the 35 cheek of the bracket. The two sections 32 are shown as being secured in position by small bolts, or the like, 34, which pass through the flanges 33 and the cheeks of the bracket. In the race-ways are the balls 35, 40 upon which rest the ends of the rock-shaft 14. It will thus be seen that the friction of the moving parts connected to the conductor 15 is greatly reduced, thereby much enhancing the reliability of the action of said 45 conductor.

In Fig. 6 is illustrated a modified form of movable electrode carrier 40, of insulation, which is divided vertically in three sections, 41, 42 and 43; the junction planes cutting the several recesses 44, which are 50 slightly more than semi-spherical. In this way, the balls 45 are held against egress, and yet are easily insertible during the assembling of the carrier 40. A further advantage is that the recesses 44 may be ground 55 out more truly than when they are formed in an integral block. The several sections of the carrier may be secured together, as by bolts 46.

What is claimed as new is:

1. In combination with an arc lamp frame having upright guide rods and a movable electrode, of a carrier block for said electrode having grooves receiving said rods and partially spherical recesses communicating with said grooves, antifriction insulating balls mounted in said recesses and bearing against said rods, and trough-shaped retainer plates fitting and secured in said grooves and having apertures communicating with said recesses, said apertures being sufficiently small to prevent egress of the balls from the recesses. 60

2. In combination with an arc lamp frame having parallel upright guide rods and a movable electrode, of a movable carrier block for said electrode having grooves at either end receiving said rods and recesses communicating with said grooves, antifriction balls of insulating material mounted in 65 said recesses to engage said rods and to separate said block therefrom. 70

Signed at New York city in the county of Kings and State of New York this 12th day of March A. D. 1908.

ABBOT A. LOW.
